UNITED STATES PATENT OFFICE.

CHARLES W. POWELL, OF GREEN ISLAND, NEW YORK.

CAR-TRUCK.

SPECIFICATION forming part of Letters Patent No. 688,686, dated December 10, 1901.

Application filed February 9, 1901. Serial No. 46,854. (No model.)

To all whom it may concern:

Be it known that I, CHARLES W. POWELL, a citizen of the United States, residing at Green Island, county of Albany, and State of New York, have invented certain new and useful Improvements in Car-Trucks, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures.

Figure 1 of the drawings is a top plan view of my improved car-truck, shown partly broken away and partly in section for convenience of illustration. Fig. 2 is a view in side elevation of the same. Fig. 3 is a view, on an enlarged scale, in side elevation of an end portion of the truck-frame, illustrating the manner in which the bearing-box for the wheel-axle is released from its slideway or housing. Fig. 4 is a top plan view of the bifurcate jaw-bit member of the housing for the axle-box, with the contiguous portion of the main frame of the truck shown in section bolted thereto. Fig. 5 is a top plan view illustrating the arrangement of the brakes and brake-operating levers and connections, the truck-frame being omitted. Fig. 6 is a vertical cross-section taken on the line 6-6 in Fig. 2 viewed in the direction of the arrow. Figs. 7 and 8 are views in side elevation of the truss members of the truck-frame.

My invention relates particularly to trucks adapted for use with electric cars.

The principal object of my invention is to provide a rigid and durable wheel-supported truck-frame with means for advantageously distributing the weight applied thereto, and, further, to provide an efficient yielding support for the car-body.

My improved truck preferably comprises two frames of general rectangular form, the lower of which is adapted to be mounted upon and supported by the car-axles. The upper

frame is longer than the lower frame, which may be part of the car-body and adapted to project at opposite ends beyond the lower frame, as shown in Fig. 2, and form a support for the car-body. (Not shown.) 1 represents 55 said upper car-body-supporting frame, and 2 2 are transversely-arranged leaf-springs mounted upon the under side thereof at opposite ends and connected with similar leaf-springs 3 3, mounted upon the lower truck-frame and projecting beyond the ends thereof, whereby the lower truck-frame is connected by such springs with the projecting portions of the upper truck-frame, thus securing widely-separated points of spring-support for 65 the car-body-supporting frame. The inner ends of said leaf-springs 3 may be connected with intermediate portions of the upper frame, as at 4.

The lower truck-frame comprises a pair of 70 trussed side frames connected by cross-bars 5 at the middle and ends, respectively.

Each side frame is preferably made of a duplicate set of parallel truss members or plates, preferably bolted or riveted together to form 75 a rigid construction. The preferred form of said plates is shown in Figs. 7 and 8, one of said plates 6 (shown in Fig. 7) having horizontal ends 7 and a depressed middle portion 8 connected with the ends by the upwardly 80 and outwardly inclined portions 9. The other truss member 10 comprises a horizontal member 11, with upturned ends 12. The plate 10 is applied to the outer side of the plate 6, and the two are bolted or riveted together at 85 their middle portions at 13, and the upwardly-projecting ends of the plate 10 are in like manner secured at 14 to the inner ends of the upper horizontal portions 7 of the plate 6, forming a rigid truss construction. The ends 12 90 of the plate 10 form the inner jaws or members of the housings or slideways for the respective axle-boxes 15, which contain the bearings for the axles 16, upon which are fixed the wheels 17 in the usual manner. The outer 95 jaw of each housing is formed by a plate 18, pivoted at its upper end at 23 upon the upper horizontal portion 7 of the plate 6 and having its lower end detachably connected, as by a bolt, at 19 with the jaw-bit member 20. This 100

jaw-bit member is bifurcated at its inner end, the ends of its bifurcate members being detachably connected with the angular end portion of the plate 10, as by bolts, at 21. The outer end of this member 20 extends diagonally upward and outward, and its outer end is connected with the outer end 7 of the plate 6 by the clevis 22, forming a pivotal connection therewith. It will thus be seen that the axle-box is provided with a housing or slide-way having its top and inner side formed by the bars 7 and 12 of the frame-plates, which constitute a rigid construction and are preferably permanently secured together, while the outer and lower sides of the same are formed by the pivoted plates or members 17 and 20, which can be released by loosening the bolt connections at 19 and 21 and swung, respectively, outwardly and downwardly to release and permit the removal of the axle-box in the manner illustrated in Fig. 3. These several frame members when bolted together form a rigid truss construction for the truck ends, as shown in Fig. 2.

As a means for advantageously distributing the weight to the truck-frame I provide a pressure equalizing and distributing bar 24, which extends transversely of the axle-box between the frame-plates and is provided on its outer end at 25 with a supporting connection with the rigid truck-frame adjacent to the point of connection of the springs 3 therewith. A coiled spring 26 is interposed between the inner end of said bar and a rigid portion of the truck-frame, as shown in Fig. 2. The intermediate portion of said bar bears or is fulcrumed upon the axle-box. It will be seen from an inspection of Fig. 2 that the upward thrust of the axle-box upon said bar will be relieved by the yielding resistance of the spring 26 and that the shock of said upward thrust of the axle-box is greatly diminished in its transmission through said bar to the rigid frame at 25. This bar acts in like manner to equalize and distribute the weight transmitted to the outer ends of the lower frame through the springs 3.

The brake mechanism of my improved truck is omitted from Fig. 1 for convenience of illustration; but a top plan view of the same is shown in Fig. 5.

The brake-shoes 30 are mounted upon the brake-beams 31, one at each end of the truck outside the wheels. The brake-beams are suspended by links 32 from the wheel-supported frame of the truck in the usual manner. Each brake-beam carries a pair of levers 33, pivoted at their outer end on said beam near its outer ends and having their inner ends pivoted together at 34. These levers 33 are connected by rods 35 each with a corresponding lever on the same side on the opposite end of the truck. The lever 36 is pivoted at one end to the middle of the brake-beam at 37 and provided at its other end with means for connecting the same with the brake-

operating shaft, as the link 38, which may connect with a chain leading to said shaft, said chain and shaft being omitted from the drawings. An intermediate portion of the lever 36 is connected by link 39 with an extension 40 of one of the levers 33.

From an inspection of Fig. 5 it will be seen that a pulling thrust exerted upon the link 38 at either end of the car will operate to produce a pull in the same direction upon the rods 35, which rods acting as a resistance will cause the levers 33 to force the brake-beam and brake-shoes toward the wheels at that end of the truck. At the same time the pull exerted upon the rods 35 will be transmitted to the levers 33 at the other end of the car to cause the brake-beam and shoes thereto to be also drawn toward the wheels. It will be seen that the levers are so arranged and connected that when those at one end of the truck are operated by the pull of the rods 35 the lever 36 at such end is drawn inwardly against the brake-beam, which arrests its movement, whereupon said lever, beam, and neighboring levers 33 become practically a rigid construction.

The system of levers at one end of the truck may be omitted and the system at the other end operated by connecting the rods 35 with any stationary support to serve as a resistance.

The jaw-bit member is preferably formed with offset ends adapted to form an abutting connection with the rigid frame member 10, as shown at 41 in Fig. 4.

I make no claim in this application to the brake mechanism shown and described herein, as the same forms the subject-matter of a separate application filed by me October 3, 1901, as a division of this application and given the Serial No. 77,398, entitled "Brake mechanism for railway-cars."

What I claim as new, and desire to secure by Letters Patent, is—

1. In a car-truck a trussed frame member comprising a rigid plate having outer horizontal end portions, a depressed middle portion, and upwardly and outwardly inclined portions connecting said middle and ends; and a rigid plate having a straight middle portion and upturned ends; said plates being applied one to the other and secured together at their middle portions, and at the junction of the upturned ends of one with the outer horizontal ends of the other, substantially as described.

2. In a car-truck, the combination with a rigid truck-frame having a horizontal rigid member forming the lower part thereof; of a jaw-bit having at one end an offsetting abutting connection with said rigid member, and at the other end an integral upwardly-extending diagonal brace connected at its upper end with an upper portion of the rigid frame, substantially as described.

3. In a car-truck, the combination with an

upper and a lower truck-frame; of a pair of leaf-springs extending longitudinally thereof and secured to one of said frames intermediate of their ends; a connection between one end of each of said springs and the other frame; a leaf-spring extending transversely of said other frame and secured intermediate of its ends thereto; and connections between the ends of said transverse spring and

the other ends of said longitudinal springs respectively, substantially as described.

In testimony whereof I have hereunto set my hand this 1st day of February, 1901.

CHARLES W. POWELL.
